(57) **CLAIM**

The ornamental design for a tissue case, as shown and described.

DESCRIPTION

FIG. 1 is a top perspective view of a tissue case in blank form. FIG. 2 is a front elevation view thereof.

FIG. 3 is a left side elevation view thereof.

FIG. 4 is a top plan view thereof.

FIG. 5 is a bottom plan view thereof.

FIG. 6 is a cross-sectional view taken along the line 6—6 of FIG. 7 of the tissue case of FIG. 1 in an assembled form; and, FIG. 7 is a top perspective view of the tissue case of FIG. 1 in an assembled form.

The broken lines in FIGS. 6 and 7 show environmental structures included to illustrate the design in an environment of use and form no part of the claimed design.

The broken lines in FIGS. 1, 4 and 5 represent perforations and are part of the claimed design. The part enclosed by perforations in FIGS. 1, 4 and 5 is shown removed in FIG. 7 in order to show the design in a condition of use.
